MELCHIOR ZWICKY, OF WYOMISSING, PENNSYLVANIA, ASSIGNOR TO TEXTILE
MACHINE WORKS, OF WYOMISSING, PENNSYLVANIA, A CORPORATION OF
PENNSYLVANIA.

THREAD-CARRIER STOP MECHANISM FOR FULL-FASHIONED KNITTING MACHINES.

1,402,033.

Specification of Letters Patent. Patented Jan. 3, 1922.

Application filed January 20, 1920. Serial No. 352,797.

To all whom it may concern:

Be it known that I, MELCHIOR ZWICKY, a citizen of the United States, residing at Wyomissing, in the county of Berks and State of Pennsylvania, have invented certain new and useful Improvements in Thread-Carrier Stop Mechanism for Full-Fashioned Knitting Machines, of which the following is a specification.

10 My invention relates to full fashioned knitting machines, and more particularly to stop mechanism for the thread-carrier rods thereof; the main object being to provide for conveniently utilizing one of the 15 ordinary thread-carrier rods for effecting the knitting of special leg courses when desired, to make the work of transferring more easy for the toppers. The invention is fully described in connection with the accompanying drawing and is clearly defined in the claims.

Fig. 1 is a cross-sectional view through an end portion of a full fashioned knitting machine, showing a thread-carrier stop nut 25 provided with my improvement and in connection with certain coacting parts.

Fig. 2 is a face view of said nut looking in the direction of arrow 2 Fig. 1; the special carrier-rod stop lever being shown 30 in operative position, with an inoperative position thereof indicated in dotted lines; and the ordinary stop lever being shown in retracted position.

Fig. 3 is a plan view corresponding with Fig. 2.

The stop nut 10 for the series of carrier rods 11, 11, corresponds in general construction and arrangement, as shown, with that fully set forth in Janssen-Zwicky Patent 40 No. 1,079,915 issued November 25, 1913; the sleeve portion 12 of said nut being engaged by the usual automatically operated thread carrier stop screw 13, and independently movable stop levers 14, 14 for the respective rods 11 being mounted upon a transverse pivot pin 15 carried by spread ears 16, 17 of the nut. The several thread carrier rods 11 are employed for different knitting operations, and are respectively 50 movable out of action when the correspond-

ing stop lever 14 is thrown to inoperative position.

Each of said stop levers 14 is adapted to positively limit the longitudinal movement of a corresponding carrier rod 11 as required; the several rod-connected friction boxes 18 on friction rod 19, to which motion is transmitted through the coulier lever 20, permitting of any slippage called for.

The operating movement of each rod 11 is thus determinedly limited by its particular stop lever 14, and its use is thus commonly restricted to a single function. In my improved construction I provide for selectively employing one or another stop so as to differently limit the operating movement of a determined rod and thus enable its employment for one or another purpose, thereby avoiding objectionable increase in the number of rods called for. As shown, 70 such additional stop 25 is separately pivoted exteriorly to the nut ear 17, with its rod contacting end portion 26 set into the line of movement of a carrier rod 11^a when in operative position, said end extending beyond that assumed by the withdrawn stop 14 so as to stop said rod 11^a a determined distance short of the maximum movement which is permitted by the latter. This rod 11^a I adapt to carry yarn of a different 80 color from the ordinary knitting thread, and the special stop lever 25 is adapted when thrown into operation in place of the regular stop 14, for the last or transverse courses of the leg, to supply such thread 85 to determined needles only and thereby provide a contrasting color which facilitates the work of transferring. This same rod 11^a may thus be used selectively for the purpose of knitting in these special transfer courses, or for another purpose as heretofore, by employing in one case the special stop 25, and in the other the regular stop 14, the thread carriers on such rod being correspondingly arranged. The provision for thus conveniently utilizing the reserve rod for either one or another purpose extends the variety of work to which the machine is adapted without objectionably increasing the working parts and with simplified operation. 100

What I claim is:

1. In a full-fashioned knitting machine having thread-carrier rods and a narrowing screw; a stop nut on said screw carrying a plurality of selectively usable stops for one rod each arranged to be moved into and out of end-abutting position.
- 5 2. In a full-fashioned knitting machine

having thread-carrier rods and a narrowing screw; a stop nut on said screw having 10 spaced-apart pivot-pin ears, a pivot pin carrying stop levers for the respective rods, and an additional stop lever for one of said rods externally pivoted to one of said ears.

In testimony whereof I affix my signature.
MELCHIOR ZWICKY.
